MARLEY FOTHERINGHAM HAY, OF GLASGOW, SCOTLAND.

VENTILATING-SHAFT FOR SUBMARINES.

1,099,127.

Specification of Letters Patent.

Patented June 2, 1914.

Application filed February 20, 1914. Serial No. 819,995.

To all whom it may concern:

Be it known that I, MARLEY FOTHERINGHAM HAY, a subject of the King of Great Britain and Ireland, and a resident of 5 Glasgow, Scotland, have invented certain new and useful Improvements in Connection with Ventilating-Shafts for Submarines, of which the following is the specification.

10 This invention relates to ventilating shafts for submarines, and has for its object to provide such shafts with an improved arrangement of valves all controlled by one handle and springs in such manner that the valves may be expeditiously operated so as either to secure effective ventilation, or to close communication with the interior of the vessel, and permit water to pass up the portion of the shaft outside the 15 hull when the vessel is being submerged. Thus it is no longer necessary to haul down the ventilating shafts preparatory to diving, and thereby the time required to prepare the vessel for diving is materially reduced. 20 Further, when such ventilating shafts are inclosed by the improved housing forming the subject-matter of a concurrent application for a patent, they present slight resistance to propulsion when submerged, and consequently this objection to their not being hauled down preparatory to diving is 25 overcome.

In carrying out the invention, a hinged valve controls communication between the 30 upper and lower portions of the ventilating shaft, that is, between the portions outside and inside the hull. This valve bears on a seat formed for it in the lower end of the upper portion of the shaft. It is operated 35 by link and lever connections from a spindle rocked by a handled lever. An aperture in one side of the upper portion of the shaft is controlled by a second hinged valve so operated by a toe piece on the hinge of the 40 first valve that when the latter is closed the second valve is forced open against the action of a spring which closes it when the toe piece is withdrawn on the opening of the first valve. An additional ventilating aperture is formed through the portion of the 45 shaft just within the hull, this aperture being controlled by a third hinged valve so positioned that it is forced open by the link connected to the first valve against the action of a spring tending to close it when the link is withdrawn on opening the first

valve. When the first valve is open, the others are closed, and air passes by the shaft to the batteries and engines with which these ventilators are connected. When the vessel 50 is to be submerged, the handled lever is so operated that the first valve is closed, the closing of this valve opening the others, as hereinbefore described. Water can then pass freely up the portion of the shaft outside the hull. If when this is taking place 55 the first valve should not be making a tight joint with its seat, any water which may leak past the valve is prevented from getting into the batteries and engines and the leak at once detected, as this water will fall on to the third valve, then open and pass into the vessel. If desired, the third valve 60 may be left open irrespective of the position of the other valves by disconnecting the 65 spring which normally holds it closed.

The improvements are shown in vertical section on an accompanying sheet of explanatory drawings.

As shown in the drawing, the lower end 70 of the upper portion A of the ventilating shaft is flanged and connected to a counterpart flange A¹, surrounding an opening formed in one side of a casing A², the lower end of which is open and secured by flanges 75 A³ in an opening formed through the hull A⁴ of the vessel. A second casing B open at top and bottom is similarly secured by flanges B¹ around the opening and projects 80 downward within the hull. From this second casing the lower portion B² of the ventilating shaft extends to the batteries and engines, or otherwise as desired, within the hull. The passage through the casing A² is controlled by a valve B³ hinged therein 85 and bearing on a seat B⁴ formed for it in the casing. The valve B³ is operated by a link B⁵, one end of which is hinged to its under side, and the other end pivoted to a lever B⁶ connected to a spindle C capable of 90 being rocked by a handled lever C¹ and extending across the lower casing B. An aperture C² in one side of the upper casing A² is controlled by a second valve C³ carried by a lever C⁴ hinged to the casing. As 95 shown, this second valve is kept off its seat by a toe-piece B⁷ on the hinge of the first valve B³ when the latter is in its closed position, and it is again forced on its seat when the toe-piece is withdrawn, as hereinafter 100 described, by a spring C⁵ extending between a projection C⁶ on the lever C⁴ and a connec-

tion C⁷ with the hull A⁴. The lower open end of the second casing B is controlled by a third hinged valve D which has on its inner side a cam strap D¹ so positioned that when the air valve B³ is on its seat the lower end of the operating link B⁵ encounters the strap and keeps the third valve D off its seat, as shown. A spring D² is connected to the valve D and to a lug D³ on the exterior of the casing B, and when the link B⁵ is withdrawn from contact with the strap D¹ by the opening of the air valve B³ as hereinbefore described, the spring D² pulls the valve D on to its seat.

15 When the vessel is to be submerged, the parts are in the position shown, that is the first valve B³ is closed and the two other valves C³ and D open, and during submer-
10 sion water can pass freely through the aper-
ture C² and up the upper portion A of the ventilating shaft, while at the same time it is prevented from passing downward. If the first valve B³ is not making a tight joint with its seat B⁴ and water should leak past
15 it, this water will fall on to the third valve and pass into the vessel. It is thus pre-
20 vented from passing down the lower portion B² of the ventilating shaft and the leak
25 is at once detected.

30 As hereinbefore described, the third valve D may be left permanently open by disconnecting the spring D². The lower end of the lower casing B then forms an additional
35 ventilating passage when the first valve B³ is open. To open the ventilator, the spindle C is rocked by turning its operating handled lever C¹ through about 180 degrees. The lever B⁶ and link B⁵ are thereby so thrown that the valve B³ is turned upward on its
40 hinge and uncovers the passage through the casing A², B. This movement of the parts withdraws the toe-piece B⁷ and the link B⁵ from contact with the valves C³ and D, re-
45 spectively, and these valves are then closed on their seats by the action of their controlling springs C⁶ and D². Free ventilation is then secured through the shaft A, B².

It will be seen that as all the valves are
50 operated by the movement of one handle only, the possibility of accidents happening owing to careless manipulation is prevented. Further, as only the valve B³ and its seat require to be sufficiently strong to resist pressure when submerged, the other parts may
55 conveniently be made comparatively light, and as these parts are in the vicinity of the highest point of the vessel, the lessening of their weight is important from the point of view of the stability of the vessel. Also
60 owing to the expedition with which the valve B³ may be closed and its position near the hull of the vessel, the chance of accidental

flooding should the ventilating shaft A be carried away in collision, for example, is minimized. In the case of the old style of 65 ventilating shaft which requires to be pulled down before the aperture through which it projected could be closed, this was always a source of danger.

What I claim is:—

1. A ventilating shaft for submarines permanently secured in position so that it extends outside and inside the hull of the vessel, valves fitted in the shaft, and means controlling the movement of the valves so that either free ventilation is obtained or the ventilation may be stopped and water permitted to pass up the portion of the shaft outside the hull when the vessel is being submerged, as described. 70

2. A ventilating shaft for submarines and comprising casings secured above and beneath an aperture in the hull of the vessel, a ventilating shaft in two portions secured to these casings so as to extend outside and inside the hull of the vessel, a valve controlling communication through the casings and shaft, a second valve controlling an aperture in one side of the upper casing, a third valve controlling the lower open end of the lower casing, and means controlling the movement of these three valves such that when the first valve is open the others are closed, and vice versa, as described. 80

3. A submarine ventilator including casings secured above and beneath an aperture in the hull of the vessel, a ventilating shaft in two portions secured to these casings so as to extend outside and inside the hull of the vessel, a valve controlling communication through the casings and shaft, a second valve controlling an aperture in one side of the upper casing, a third valve controlling the lower open end of the lower casing, a link hinged at one end to the first valve, 95 a lever to which the other end of the link is hinged, a rocking spindle to which the lever is connected, a handled lever operating the rocking spindle, a toe-piece on the first valve capable of bearing on the second valve, 100 a cam strap on the third valve on which the lower end of the link may act, so that the toe piece and link hold the second and third valves open when the first valve is closed, and springs closing the second and 110 third valves when freed. 105

In testimony whereof I have signed my name to this specification, in the presence of two subscribing witnesses.
